UNITED STATES PATENT OFFICE.

FRANZ BURGER, OF FORT WAYNE, INDIANA, ASSIGNOR OF THREE-FOURTHS
TO HENRY M. WILLIAMS, OF SAME PLACE.

SPEED-REGULATOR FOR EXPLOSIVE-ENGINES.

SPECIFICATION forming part of Letters Patent No. 679,883, dated August 6, 1901.

Application filed May 3, 1899. Serial No. 715,442. (No model.)

To all whom it may concern:

Be it known that I, FRANZ BURGER, a citizen of the United States, residing at Fort Wayne, Allen county, State of Indiana, have invented 5 certain new and useful Improvements in Gas-Engines, of which the following is a specification.

My invention relates to balanced gas or gasoline engines, the object being to provide such 10 an engine which shall be capable of running at relatively very high speeds and which shall operate at a practically uniform rate of speed, the explosion taking place at each rotation, and which shall be simple and compact in construction; and to these ends my 15 invention consists in the various features of construction and arrangement, substantially as hereinafter more particularly set forth.

Referring to the accompanying drawings, 20 Figure 1 is a vertical section of an engine embodying my invention; and Fig. 2 is a vertical section, the ends of which are taken on the line 2 2 of Fig. 1, and the central portion is a partially-broken elevation and a central section, 25 one of the pitmen being shown in full line throughout its length.

My present invention is more particularly an improvement on the engine patented to me November 12, 1895, No. 549,626, and the 30 engine proper to which my present invention is applied is practically the same as that described and shown in said patent.

My present improvements relate more particularly to the improved means of governing 35 and controlling the supply of air and gas or other fuel of combustion, and I will specifically describe the embodiment of my improvement in this case and describe enough of the engine proper to enable it to be understood, 40 the particular details of the construction of the engine being more fully set forth in said patent above referred to. Said patent shows a governing device which, while it is effective, is under some conditions open to objection, and my present improvement is intended 45 to be used where the governing device shown in my prior patent would be undesirable or the present improvement would be more effective.

50 Briefly describing the engine proper, it consists, as shown, of a base B, constituting a

crank-shaft chamber H, which is provided with heads B', which furnish bearings for the shaft H', which shaft is provided with cranks H² H³ H⁸ and a balance-wheel H⁴. Connected 55 to the base is a working cylinder B², which is provided with suitable passages for the air and gas and preferably with water-jackets B³ wherever desired. The cylinder is also provided with lateral extensions B⁴, which form 60 communicating passages L between the crank-shaft chamber H and a cross-head chamber J, inclosing the connecting-rods M between the cranks H³ and the cross-head O. The cross-head chamber is formed in the present instance by a cap-piece B⁵, secured to the cylinder B². Mounted in the working cylinder 65 are two pistons C and D, the former being connected to the cross-head O and the latter being connected to the crank-rod D', mounted 70 on the crank H² of the shaft. The cranks H² and H³ are so arranged as to form a two-throw crank, which will cause the pistons to simultaneously approach or recede from each other. The combustion-chamber W is located 75 between these pistons, and there are suitable inlet-ports E and exhaust-ports F arranged to be opened and closed by the movement of the respective pistons.

The engine is provided with a suitable igniter G.

Thus far the construction is practically the same as in my prior patent, and that patent shows the cross-head chamber J serving as a reservoir for the supply of air and gas or 85 other fuel and a pipe M', leading from said chamber to the inlet-ports E, controlled by an automatic governor. In the present instance the supply of air and gas may be from the same source or from any other, it being 90 supplied in some suitable way to the passage E', communicating with the ports E.

I dispense with the governing-valve shown in my prior patent, and in my present construction I utilize one of the pistons to control the admission of air and gas and provide means for regulating or adjusting the movements of said piston in accordance with the requirements of the engine, or, in other words, I arrange the parts so that the piston 95 will move more or less and open or close the inlet-ports partly or wholly, in accordance

with its speed or the work done. In the present instance I so utilize the upper piston C and control its position with relation to the ports by an ordinary speed-governor, although of course any other governing device can be used for automatically controlling the piston.

In the present instance as the piston C is reciprocated by the connecting-rod M, operated by the cranks H³, I mount the piston 10 on the cross-head O, as before, but connect the cross-head and rods by means of an eccentric or crank, so that by properly adjusting the position of the cross-head with relation to the connecting-rods M the relative 15 movement of the piston can be regulated with respect to the inlet-ports E. Thus the cross-head O is provided at its ends with cranks P, to which the connecting-rods M are attached. Connected to one or both of the 20 cranks (only one being shown and being found sufficient) is a lever Q, preferably provided at its outer end with a friction-roll q. In the frame of the machine I provide a slot R, in which the end of the lever Q moves, 25 and this slot in the frame is arranged parallel with the central axis of the piston, so that as long as the lever Q moves in the slot the distance apart of the driving-crank and the cross-head remains the same. When, however, 30 the end of the lever is diverted so as to travel out of a parallel line with the movement of the piston, of course the relations are changed and the distance between the driving-crank and the cross-head is extended 35 or contracted, as the case may be. In order to do this automatically, I provide what may be termed an "adjustable slot extension" S, which is shown in the present instance in a shape somewhat resembling a horseshoe pivoted at one end to the frame of the engine. This horseshoe or extended slot is connected 40 by suitable mechanism to a governor I, shown in the present instance as an ordinary ball-governor connected to be driven in some suitable and usual way from the engine and having 45 a link I' connected to a projection S' on the horseshoe, so that it will be rocked to adjust the slot extension at an angle to the vertical slot, according to the speed of rotation of the 50 engine. With this construction it will be seen that when the governor is in its contracted position and the engine at rest the horseshoe or extended slot portion S will be in a vertical position, (shown in dotted lines,) forming a 55 practical continuation of the slot R, and the friction-roll on the lever Q will travel through this slot and maintain the normal relations of the crank-shaft and piston. It is preferable under these conditions that the cranks 60 P should be in alinement with the cross-head O and axes of the cranks H³, so that the piston will be in its most elevated position, fully opening the ports E. When, however, the engine starts and the governor operates, the 65 horseshoe will be inclined to a greater or less extent and the friction-roll q will follow the slot extension, which will partially rotate the

cross-head, so as to swing the cranks P out of a direct line, thereby shortening the distance between the cranks and the cross-head, so that at each reciprocation the ports E will only be partially opened and to an extent depending upon the inclination of the horseshoe, and this inclination will depend upon the speed of the engine by means of which it is automatically regulated. In Fig. 2 the parts are in a position showing the piston uncovering about one-half of the inlet-ports. If the engine is operating too rapidly, the governor will rotate the cross-head to such an extent that this relation will be changed, so that the inlet-ports will be uncovered only slightly, or perhaps not at all.

It will be observed that the force of the explosion operating the piston will tend to 85 keep the cranks P substantially vertical, and this will operate against the controlling force of the governor; but as the piston approaches the limit of its motion the force of the governor is sufficient to change the position of 90 the horseshoe, so that the regulation of the movement of the piston is quickly and accurately attained, and the changing takes place toward the latter movement of the piston when the expansive force of the air and gases 95 has done its work to nearly the full extent, and especially in the present instance, where there are two pistons used, the lower one controlling the exhaust, the pressure on the upper piston from the expansive gases is nearly, 100 if not quite, relieved at the time the piston reaches its upward limit and can be easily and readily controlled by the governor, and thus in turn control the inlet-ports. While I have shown this mode of regulating the inlet-ports by changing the relative movements 105 of the piston in an engine having two pistons moving to and from each other, it is evident that the same principles could be applied to engines having but one piston, which governs 110 the inlet, and the outlet is governed in the usual manner.

What I claim is—

1. In a gas-engine, the combination with a working cylinder having inlet-ports, of a piston within the cylinder for controlling said inlet-ports, a governor and connections between the same and the piston whereby the stroke of the piston is varied to automatically regulate its movement to open and close 115 the ports to a greater or less extent during the operation of the engine, substantially as described.

2. In a gas-engine, the combination with a working cylinder having inlet-ports, of a piston within the cylinder for controlling said ports, connections between the piston and the power-giving parts of the engine, a governor and connections between the same and the piston whereby the stroke of the piston is varied to automatically regulate its movement thereby controlling the opening and closing 125 of the inlet-ports during the operation of the engine, substantially as described.

3. In a gas-engine, the combination with a working cylinder having inlet-ports, of a piston mounted therein controlling the ports, reciprocating connections between the piston and the power-giving parts of the engine, cranks or eccentrics between the connections and the piston, and a governor for automatically controlling the relation of such cranks to the piston during the operation of the engine, substantially as described.
4. In a gas-engine, the combination with a working cylinder having inlet-ports, of a piston controlling said ports, driving-cranks, connecting-rods between the piston and driving-cranks, an eccentric or crank between the connecting-rods and piston, and a governor for automatically changing the relation of said cranks to the piston during the operation of the engine, substantially as described.
5. In a gas-engine, the combination with a cylinder having inlet-ports, of a piston reciprocating therein and controlling said ports, an eccentric connected to the piston, a lever connected to the eccentric, a slot in the frame of the machine in which said lever operates, an adjustable slot extension, and a governor connected with said slot extension whereby the movements of the piston with relation to the ports are controlled, substantially as described.
6. In a gas-engine, the combination with a working cylinder provided with inlet-ports, of two pistons therein the length of movement of one of which pistons is constant and that of the other piston is variable, a governor and connections between the same and the latter piston whereby the stroke of said piston is varied to automatically regulate its movement to open and close the ports to a greater or less extent during the operation of the engine, substantially as described.
7. In a gas-engine, the combination with a working cylinder provided with inlet and outlet ports, of two pistons therein, one of which controls the inlet and the other controls the outlet ports, a governor and connections between the same and the former piston whereby the stroke of said piston is varied to automatically regulate its movement to open and close up said inlet-ports during the operation of the engine, substantially as described.
8. In a gas-engine, the combination with an explosion-chamber, provided with inlet and outlet ports, of two pistons therein, a two-throw crank adjacent to the cylinder, a pitman from each piston to said crank, a crank-shaped cross-head between one of the pistons and its pitman, and means for rotating said cross-head, substantially as set forth.

In testimony whereof I have signed my name to this specification in the presence of two subscribing witnesses.
